(57) **CLAIM**

The ornamental design for a brush cleaning utensil, as shown and described.

DESCRIPTION

FIG. 1 is a front perspective view of a brush cleaning utensil showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof; and,

FIG. 9 is a reference view showing the design in use.

The broken lines depict portions of the brush cleaning utensil in which the design is embodied that form no part of the claimed design.
